(57) **CLAIM**

The ornamental design for an oximeter, as shown and described.

DESCRIPTION

FIG. 1 is a perspective view of an oximeter showing my new design.

FIG. 2 is a front view of an oximeter.

FIG. 3 is a rear view of an oximeter.

FIG. 4 is a left side view of an oximeter.

FIG. 5 is a right side view of an oximeter.

FIG. 6 is a top view of an oximeter; and,

FIG. 7 is a bottom view of an oximeter.

The broken lines depict portions of the oximeter that form no part of the claimed design.
